UNITED STATES PATENT OFFICE

RALPH E. DORMAN, OF NITTANY, PENNSYLVANIA

DOUBLE ACTION RATCHET BRACE

Application filed August 31, 1931. Serial No. 560,287.

This invention is a double action ratchet brace for wood boring and the like.

One object is to provide a boring tool operable in comparatively restricted places, such as corners or laterally through joists under floors.

Another object is to provide a tool of the kind referred to having a lever operated chuck, the latter being adapted for continuous rotation in either direction desired, under the oscillating driving action of the lever.

Another object is the provision of a ratchet boring brace operable through an oscillating hand lever and through a gear train transmitting the lever action to the chuck, there being a reversible ratchet control for the gear mechanism, whereby the chuck may be caused to rotate continuously in either direction notwithstanding the oscillating motion of the handle.

With these and such other objects and advantages as may appear, attention is called to the following specification and to the accompanying drawings as constituting a part thereof and wherein

Figure 1 is a side elevation of the tool assembly, the rotatable connection between handle and chuck being in section to show the arrangement of the adjustable lock ball races and ball bearings;

Figure 2 is an enlarged detail of the medially mounted gear train or system for driving the chuck, portions of the handle and chuck being broken away;

Figure 3 is a section on the line 3-3 of Figure 1;

Figure 4 is an enlarged section on the line 4-4 of Figure 1;

Figure 5 is an enlarged section on the line 5-5 of Figure 3;

Figure 6 is an enlarged section on the line 6-6 of Figure 1.

The invention comprises a handle bar 1 with hand knob 2 at its upper end, having a medially located, transversely extended and preferably integrally formed gear shaft hub 3 and having its lower end journaled and threaded as shown at 4. A gear shaft 5 is passed tightly through the hub 3 and

a pair of bevel gears 6 and preferably integrally connected and smaller ratchet gears 7 are freely mounted upon the ends of this shaft. Side plates 8 having inturned margins 9 are set over the outer sides of these gears, the plates having holes 10 through which the ends of the shaft 5 are passed. Bushings 11 are then set over the ends of the shaft 5 and into the holes 10 of the plates, the plates having holes 10 formed through them adapted to align with the ends of the shaft 5. Threaded bores 12 are extended into the ends of the shaft 5 and set screws 13 are set thereinto with their heads overlying the bushings 11 and thus locking the gears in place. A spacer 14 is provided with side plates 15 extended within the plates 8, and set screws 16 are passed through the plates 8 and 15 and through spacing bushings 17 into threaded bores 18 formed in the spacer 14. Additional set screws 19 are passed through the outer ends of the plates 15 into the spacer. An operating lever 20 has an end threaded at 21 into the front side of the spacer 14, and a ratchet control plate 22, having the inturned pawl engaging fingers 22a, is pivotally mounted at the front of the spacer 14 over the end of the lever 20, which passes freely through said plate, the latter being held against lateral displacement by a nut 23 and set screw 24. Two pairs of oppositely arranged pawls 25-26 are loosely pinned at 27 to the inner faces of the side plates 8, the inturned margins 9 of which are cut out as shown at 28 to permit the free play of said pawls as well as to permit access thereto. The inner ends of the pawls are adapted to shiftingly engage the ratchets 7 at either side, while outer ends are freely disposed within the fingers 22a. Expansion springs 29 are braced between the pawls so as normally tend to throw them into engagement with the ratchets, but by shifting the control plate 22 either up or down, the fingers 22a at either end will operate to force a lower pawl 25 at one side out of engagement with its ratchet, and simultaneously an upper pawl 26 at the opposite side out of engagement with its ratchet. The springs 29 are en-

closed within tubular guides or sleeves 42 and at their ends enter seats or sockets 43 formed in the pawls. Thus an upper pawl 26 at the first side and a lower pawl 25 at 5 the opposite side will remain in engagement with their respective ratchets. Under this arrangement, it is obvious that oscillation of the lever 20 in a plane passing through the axis of the handle bar 1 will result in 10 the continuous rotation of the ratchets 7 and connected gears 6 in the same direction, since the pawls alternately engage their ratchets at top and bottom on opposite sides of the gear assembly. A lock screw 30 is thread- 15 edly passed through the plate 22 and the inner end slidably engages a series of corrugations 31 formed in the face of the spacer 14, whereby the latter is yieldingly retained in any adjusted position. A lock nut 32 may 20 be provided for the screw 30. A connecting bevel ring gear or chuck gear 33, having a sleeve 34 exteriorly threaded at 35, is rotatably mounted upon the lower end of the handle bar 1 in mesh with the gears 6, and 25 a pair of interiorly threaded ring-like ball races 35 threadedly engaging the threaded end of the bar 1 and lockingly turned against one another, serve to lock the gear 33 to the bar. Ball bearings 36 are interposed be- 30 tween the sleeve 34 and the upper ball race 35. A chuck assembly 37 of conventional form, is provided at its upper end with a rigidly connected socket 38 interiorly threaded and mounted upon the sleeve 34, 35 with a ball bearing 39 interposed between the bottom of the socket and the lower ball race 35. A set screw 40 serves to lock the assembly together. Thus the chuck 37 will 40 freely rotate under the rotation of the gears 6. By adjusting the rings 35 and jamming them together, and adjusting the socket relative to the sleeve 34, the chuck will smoothly rotate relative to the stationary handle bar 1. 45 It is thought the use and operation of the tool will be fully understood from the foregoing description.

While I have herein described a certain specific manner and method of constructing and assembling the elements of my invention, it is understood that I may vary from the same in minor details, not departing from the spirit of my invention, so as best to construct a practical device for the purpose intended, as defined in the appended claims.

I claim:

1. In a tool of the kind described, a handle bar, a chuck assembly journaled at one end 60 of the handle bar, a beveled chuck gear connected to the chuck assembly and journaled on the handle bar, a gear shaft extended diametrically through the handle bar above the chuck gear, beveled gears journaled on 65 the gear shaft on opposite sides of the handle

bar and meshing with the chuck gear, ratchet gears on the outer sides of the bevel gears, side plates journaled on the ends of the gear shaft outwardly of the said ratchet gears, a spacer, side plates on the spacer 70 extended within and connected to the said side plates in spaced relationship therewith, an operating lever secured to the spacer, two pairs of oppositely arranged pawls fulcrumed on the inner sides of the outer side plates the said pawls being adapted to engage the ratchet gears at their inner ends, expansion coil springs braced between the outer ends of each pair of pawls and adapted 75 to normally hold the inner ends of the pawls in engagement with the ratchet gears, a ratchet control plate journaled on the operating lever alongside the spacer, fingers turned inwardly from the edges of the ratchet control plate and adapted to engage 80 the outer ends of the pawls, and means for securing the ratchet control plate in an adjusted position.

2. In a tool of the kind described, in combination with a pair of spaced beveled gears journaled on a gear shaft and driving a chuck assembly, ratchet gears carried by the beveled gears, side plates journaled on the gear shaft, a spacer secured between the outer ends of the side plates, an operating lever 90 extended from the spacer, a pair of pawls fulcrumed on each side plate and adapted to engage the ratchet gears upon opposite sides, expansion coil springs braced between the outer ends of the pawls and adapted to normally urge the inner ends of each pair of pawls, together into engagement with the ratchet gears, a pawl operating plate pivotally mounted on the spacer, fingers extended 95 inwardly from the opposite margins of the pawl control plate and adapted to engage the outer ends of the said pawls, whereby either diagonally opposite pair of pawls 100 may be released from the ratchet gears.

In testimony whereof I affix my signature.

RALPH E. DORMAN.
